APPARATUS FOR TRANSFERRING BOXES
FROM A FILE

Ernst Hermann Jähne, Dresden, Germany, assignor to "Universelle" Cigarettenmaschinen-Fabrik, J. C. Müller & Company, Dresden, Germany

Application February 24, 1931, Serial No. 517,995,
and in Germany July 26, 1930

11 Claims. (Cl. 198—35)

Filled boxes or the like must frequently be subjected to further treatment, that is provided with a sealing strip or the like. In these circumstances it is important that once the boxes or the like are filled they should not be subjected to any further serious jolting likely to injure the contents of the boxes. It is well known, for instance, that in the case of boxes filled with cigarettes, jolting or the like damages the ends 5 of the cigarettes and causes the tobacco at the ends to crumble away.

The object of this invention is to convey the ready-filled and stacked boxes to the position where they are further treated so that for practical purposes they are sufficiently free from concussion, taking into consideration the fact that the boxes must arrive at such position lying flat on an horizontal table, while on the other hand it is impossible to insert the filled boxes in 15 special magazines or the like owing to the shaking it involves.

The articles are therefore simply deposited on a horizontal or approximately horizontal "pile" table on which they are arranged erect and in 20 serial order. This pile is moved forward and, each time, the foremost article of the pile is displaced in a vertical direction by a member which 25 engages with it frictionally so that there is an instant increase in the forwarding speed in such manner that a catch or the like can perform the further delivery in a manner sufficiently free from concussion for practical purposes; this being done along a curved path so that the box is transferred from the vertical position to a flat position 30 and arrives in this position on the feed table where, by means of further catches or the like, it is carried to the position where it is subjected to further treatment.

The apparatus for carrying out the process is 35 preferably constructed in such manner that the pile of boxes is transferred to a conveyer belt which carries away the foremost box by friction and passes it to an adjacent curved guideway; a gripping member fixed to an endless 40 chain or the like, which moves at the same or at a somewhat greater speed than the delivery speed of the belt, seizes the box totally or partially transferred to the curved guideway, and while moving parallel to the guideway delivers 45 the article to the horizontal reception table.

The annexed drawing shows a vertical longitudinal section of one form of construction of the apparatus.

The filled boxes *a* are deposited erect on the 50 upper surface *1* of an endless belt, which runs

over a table *2* inclined towards the delivery position of the articles, and is returned over the guide rollers *3*, *4*, *5*. The guide roller *4* is driven by means of a belt or a chain *6*.

The pile of articles on the side *1* of the "pile" belt is driven forward in the direction of the arrow towards the side *7* of an endless belt passing over the guide rollers *8* and *9*. The surface *7* of this endless belt is so arranged that it runs parallel or approximately parallel to the end wall of the front box facing it. By means of gearing *10*, *11* a guide roller *9* is driven so as to impart a downward movement to the working surface *7* of the endless belt. The gear wheel *10* engages with a driving wheel *12* mounted on the axle of a sprocket wheel *13*. Over this sprocket wheel there passes a chain *14* which also runs over a second sprocket wheel *15* and causes a transfer of the articles to a guide channel *16* which is arcuate, so that it transfers the boxes delivered to it from the original vertical or approximately vertical position to the horizontal position and then delivers them flat to an adjacent horizontal table *17*.

The chain *14* is provided at regular intervals with catches *18*, which are arranged in such manner that they engage the articles which have arrived in the guide channel and pass them through the latter. The apparatus is so designed that first the foremost box of the pile is carried away by friction by the working surface *7* of the conveyer belt and drawn downwards from the pile. In this operation there is practically no shock. The box then acquires the acceleration of the conveyer belt and is engaged by the respective catch *18* of the chain *14* before the action of the surface *7* on the box has finished. The box has, however, already partially entered into the guide channel *16*, so that the catch can pass the box through the guide channel practically without shock.

The chain is driven by the belt *19*, of which the pulley *20* is fixed to the axle of the sprocket wheel *15*. This axle actuates the driving wheel *23* for the chain *6*, through the gearing *21*, *22*.

In the form of construction illustrated, the boxes deposited on the table *17* by the respective catches *18* are thrust forward still further and then transferred to a catch *24* which is fixed to an endless chain *25*. This chain is passed over a sprocket wheel *26* in such manner that the working surface of the chain runs parallel to the surface of the table *17*, that is to say horizontally. At the moment when the catch *18* leaves the box it is engaged by new catches *110*

24 and passed on to the table 17 to the position where it is subjected to further treatment.

In order that the second article in the pile should not fall over while the first article is being removed by the surface 7 of the conveyer belt, a brush roller 27 is provided which is mounted on the end of a swinging arm 28, which in its turn pivots about the axis of the sprocket wheel 13. The brush roller is applied, after the manner of a brake, to the pile in the vicinity of the second article and holds it firmly in an erect position until the pile, after the removal of the first article, can be thrust forward towards the conveyer belt surface 7.

Having thus described the nature of the said invention and the best means I know of carrying the same into practical effect, I claim:—

1. An apparatus for transferring filled boxes without shock from a pile to a position where they are subjected to further treatment comprising a conveyor belt, means for pressing a pile of boxes against said conveyor belt so that said conveyor belt may remove the foremost box by friction, a curved guideway, an endless chain traveling along said curved guideway, means upon said chain for engaging said foremost box which has been entirely or partly transferred to said curved guideway by said conveyor belt and means for moving said endless chain at approximately the delivery speed of said conveyor belt.

2. Apparatus according to claim 1, said means for pressing the pile of boxes comprising a second conveyer belt which is preferably inclined towards the delivery position for the pile of boxes and means for moving said second conveyor belt towards the first conveyer belt which engages the foremost box by friction.

3. An apparatus according to claim 1 in which a brush roller is positioned above the pile in order to slightly restrain the second article of the pile to prevent said second article from falling while the first article is being displaced.

4. An apparatus according to claim 1 with means for restraining the second article of the pile to prevent it from falling while the first article is being displaced.

5. An apparatus for transferring filled boxes without shock from a pile to a position where they are subjected to further treatment comprising a conveyor belt, a second conveyor belt for moving a pile of boxes against said first mentioned conveyor belt so that the latter may remove the foremost box by friction, a curved guideway, an endless chain traveling along said curved guideway and means upon said chain for engaging said foremost box which has been entirely or partly transferred to said curved guideway by said first mentioned conveyor belt to guide the same along said curved guideway.

6. An apparatus for transferring filled boxes without shock from a pile to a position where they are subjected to further treatment comprising a conveyor belt, a second conveyor belt for moving the pile of boxes against said first mentioned conveyor belt so that the latter may remove the foremost box by friction, a curved guideway, an

endless chain traveling along said curved guideway, means upon said chain for engaging said foremost box which has been entirely or partly transferred to said curved guideway by said first mentioned conveyor belt to guide the same along said curved guideway and means for moving said endless chain at approximately the delivery speed of said first mentioned conveyor belt.

7. An apparatus for transferring filled boxes without shock from a pile to a position where they are subjected to further treatment comprising a conveyor belt, means for pressing a pile of boxes against said conveyor belt so that said conveyor belt may remove the foremost box by friction, a chute, an endless chain traveling along said chute and means upon said chain for engaging said foremost box which has been entirely or partly transferred to said chute by said conveyor belt.

8. An apparatus for transferring filled boxes without shock from a pile to a position where they are subjected to further treatment comprising a conveyor belt, means for pressing a pile of boxes against said conveyor belt so that said conveyor belt may remove the foremost box by friction, a chute, an endless chain traveling along said chute and means upon said chain for engaging said foremost box which has been entirely or partly transferred to said chute by said conveyor belt and means for moving the said endless chain at approximately the delivery speed of said conveyor belt.

9. An apparatus for transferring filled boxes without shock from a pile to a position where they are subjected to further treatment comprising means for transferring a pile of boxes arranged in substantially vertical relation, means for removing the foremost box so as to allow the same to fall under the influence of gravity, means for accelerating the fall of said box and means for guiding said box so as to transfer said box from its substantially vertical position to a substantially horizontal position.

10. An apparatus for transferring filled boxes without shock from a pile to a position where they are subjected to further treatment comprising means for feeding a series of boxes in substantially vertical position so that the foremost will fall under the influence of gravity, an endless belt for increasing gradually said gravitational fall of said box, and a curved chute into which said box falls to change the position of said box from a substantially vertical to a substantially horizontal position.

11. An apparatus for transferring filled boxes without shock from a pile to a position where they are subjected to further treatment comprising an endless conveyor for moving a series of boxes in substantially vertical position to a point where the foremost box will fall under the influence of gravity, an endless belt for accelerating the fall of said foremost box and means cooperating with said endless belt for changing the position of said box from a substantially vertical position to a substantially horizontal position.
